DYNAMO ELECTRIC MACHINE ARMATURE

Application filed November 23, 1927. Serial No. 235,281.

This invention relates to improvements in that type of armatures having two separate and distinct windings either of which may produce or receive current independently of the other. One of the objects of the invention is to provide a structure having a maximum of the core and winding material effectively employed together with such methods of producing said structure as will result in an article of greater durability than when made according to present methods.

Another object of the invention is to provide a commutator the segments of which are composed of integral ends of the conductor bars.

Another object of the invention is to provide conducting loops which may be economically made from bars of such cross section as to be suitable for commutator segments.

Another object of the invention is to provide a winding and commutator in continuous circuit without soldered, brazed or welded joints therein.

Other objects will become apparent to those skilled in the art as the invention is described in detail and reference is made to the drawings wherein—

Fig. 1 shows a length of bar stock which has been cut apart to form two conductor bars of different length and form.

Fig. 2 shows how the conductor bars are spaced apart in loop form prior to entry into a core.

Fig. 3 shows several loops Fig. 2 assembled with a portion of a core, the ends of the shorter conductor bars being displaced away from the axis of the core which permitted the longer bars to be bent to loop form as shown.

Fig. 4 shows the structure Fig. 3 after the ends of the shorter conductor bars have been replaced to pair them with the longer ends to form commutator segments.

Fig. 5 shows a core having an integral commutator and winding assembled therewith and molded insulation binding them together,

space being left in the core for the second winding.

Fig. 6 shows a completed double wound armature having a winding of relatively fine wire filling the remaining space in the core slots and a commutator connected thereto.

Similar numerals refer to similar parts throughout the several views.

In carrying out my invention I prefer to use, for the conductor bars of the coarser winding, stock of wedge shaped cross section, such as is commonly used to compose segments of a dynamo electric machine commutator.

In Fig. 1 is shown a length of such stock which has been cut apart at 20, forming from the piece a conductor bar 21 having a beveled end 22, and a relatively longer and differently shaped conductor bar 23, having an upwardly projecting end 24 beveled at 25 and 26, the two conductor bars being left joined together at the end 27.

After a length of stock is cut apart as in Fig. 1, it is bent as at 28 Fig. 2, the two conductor bars 21 and 23 throughout part of their lengths extending substantially parallel and spaced apart sufficiently to compose a turn of the winding.

In Fig. 3 I show a portion of a core 29 into which several winding turns have been assembled and while the core shown has semi-closed slots 30, 30 etc., the winding shown may be readily applied to cores having slots that are entirely closed or entirely open. The conductor bars in Fig. 3 are shown to have been further bent, this time at 31, 31 etc., to complete the winding turns and while the bends at 31, 31 etc., are such as to compose the turns of a lap winding, it is obvious that had these bends been made in an opposite direction the turns of a wave winding would have been formed.

To permit bending as at 31, 31 Fig. 3 without having the ends 24 interfere with the ends 32 when bending is taking place, the

ends 32 may be displaced outwardly from their true position relative to the core axis as shown. This displacement may be made in the loops Fig. 2 before they are endwise entered thru the slots 30, since slots 30 are intended to receive two separate windings and are therefore of greater depth than required by bars 21 and 23 in normal position.

6 After the conductor bars 23 are bent, as in 31, 31 Fig. 3, the shorter bars 21 are replaced to their position nearer the core axis, as shown in Fig. 4, where they are arranged with an end 32 of an outer layer bar 21 circumferentially adjacent to an outwardly projecting end 24 of an inner layer bar 23, pairs thus formed serving not only to connect the turns of the winding in continuous circuit, but also forming of each pair a commutator segment.

15 20 Cases may arise however, where it is desirable to use such a winding without using the connecting ends as a commutator, in which case the outwardly projecting portion 24 of the bar 23 need not be as long in proportion to the bar here shown. L shaped spacers 25 33, 33 etc., of mica or other insulating material may be placed between the several segments as shown, but must not be placed between any two ends comprising a segment.

20 30 One of the novel features of the invention resides in the manner of making the integral conducting and commutator parts hereinbefore disclosed. When the upwardly projecting end 24 of bar 23 (see Fig. 1), is intended 35 to form part of a commutator segment, it is desirable that it extend lengthwise of the bar sufficiently for that purpose, and when so cut from a single bar the part remaining composing the conductor bar 21 will of necessity be shorter than the bar 23. In Fig. 2 and Fig. 3 the portions 28 and 31 forming the leads or end connections between the two conducting bars of a turn are composed 40 entirely of the longer conducting bar and it is because of this manner of forming the 45 turn that the two ends 24 and 32, Fig. 4, comprising a pair, can, when so desired, be brought to equal distances from the end of the core in the completed winding, the bent 50 portions 28 and 31 taking up the extra length of one bar of a turn over the other.

55 Cases may arise where the two bars of a turn are of such proportion as to length as to necessitate forming end connections at both ends from both bars, the longer bar supplying a greater portion of such lead or end connection than the shorter, and while I show one form which the end connections may take it is obvious that these ends may be bent to 60 any form or contour which will connect the spaced apart bars of a turn without interference of one end connecting portion with another.

65 After all the slots of a core have been wound like the several slots shown in Fig.

4 the assembled structure is preferably placed in a mold and insulating material molded thru and about the ends of the conductor bars to bind them together and form a commutator thereof.

70 In Fig. 5 I show cores with integral windings and commutators so constructed, where in 34 is the insulating material used as a binding means. After completing the one 75 independent winding, Fig. 5 as disclosed, the spaces 35, 35, etc., (see Fig. 4), remaining in the slots 30 of core 29 may be used for another winding which will usually be composed of a number of turns of relatively fine 80 wire 36 wound in coils in continuous circuit and tapped at intervals and connected to the bars of a separate commutator 37, as shown in Fig. 6. This separate commutator 37 may be mounted at the end shown or it may surround the coarser winding and be fastened thereto at the same end as the commutator of the first winding, and while I show the second winding to be composed of coils of many turns of relatively fine wire, it may be composed of coils of fewer turns of coarser 85 wire or of coils of several turns of insulated strip stock.

90 While I have herein shown and described one embodiment of my invention, it is obvious that many changes in the details of the structure may be made without departing from the spirit of the invention, the scope of which I aim to define in the following 95 wherein—

100 I claim—

1. The method of winding a double wound armature which consists of splitting lengths of commutator bar stock from a point near one end to a point near the other, thence outwardly through one edge so as to provide long and short legs, bending the long legs sidewise to take up substantially half of the excess length of the long over the short legs, bending the short legs outwardly, inserting a plurality of the bars endwise thru the winding apertures, bending the long legs sidewise to take up the remainder of their excess length, bending the short legs inwardly, binding together pairs of ends, each pair composed of an end of a short leg and an end of a long leg, to compose commutator segments and the segments together to compose a commutator, placing a relatively fine wire winding in the space remaining in the apertures and connecting it to a separate 110 commutator.

115 2. A double wound dynamo electric machine armature comprising, a magnetizable core containing a plurality of radially deep winding apertures, a bar winding arranged in two concentric layers in the inner half of said apertures, said winding being composed of a plurality of loops each comprising a single piece of metal having two spaced 120 apart legs, one leg being a conductor bar of 125

the inner layer and the other leg being a conductor bar of the outer layer, the conductor bars of the inner layer terminating in enlarged ends which extend upwardly along-
5 side bars of the outer layer, means to bind the ends of bars of the outer and inner layers together to compose commutator segments, and the segments together to compose a com-
10 mutator, and a wire winding in the outer half of the winding apertures overlying the bar winding.

In testimony whereof I hereunto subscribe my name.

VINCENT G. APPLE.
